(57) **CLAIM**

The ornamental design for a heater for a vaping device, as shown and described.

DESCRIPTION

FIG. 1 is an isometric view of a heater for a vaping device showing my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a first end elevation view thereof; and,

FIG. 7 is a second end elevation view thereof.

The broken lines in the drawings depict portions of the heater for a vaping device that form no part of the claimed design.
